UNITED STATES PATENT OFFICE.

ARTHUR H. ADAMS, OF SPARKILL, NEW YORK, ASSIGNOR TO WESTERN ELECTRIC COMPANY, OF NEW YORK, N. Y., A CORPORATION OF ILLINOIS.

PRINTING-MACHINE.

1,128,649.

Specification of Letters Patent. Patented Feb. 16, 1915.

Application filed February 12, 1912, Serial No. 677,021. Renewed February 3, 1914. Serial No. 816,335.

To all whom it may concern:

Be it known that I, ARTHUR H. ADAMS, a citizen of the United States, residing at Sparkill, in the county of Rockland and 5 State of New York, have invented a certain new and useful Improvement in Printing-Machines, of which the following is a full, clear, concise, and exact description.

This invention relates to printing machines and its object is to provide improved mechanism for automatically and continuously supplying to a laterally movable carriage the paper or other medium to be printed upon, in such a way as to avoid distorting 10 or tearing it. To this end a roller holder for the paper is arranged to coöperate with the laterally movable paper carriage of a printing machine in such a manner that the paper to be printed upon is fed from the roll 15 holder directly to the carriage, without the use of intermediate twisting members, the paper strip being given a single partial twist over itself and at approximately ninety degrees, so as to approach the carriage at 20 substantially a right angle, whatever the position of the carriage may be.

Preferably the roll holder is located below the printing platen in a vertical position and pivoted at its upper end. A particularly 30 convenient and simple pivotal mounting is provided by making the roll holder tubular with a closed upper end, which rests in a point center bearing upon the end of a vertical standard or support extending up 35 through the tube.

In the drawings—Figure 1 is a view showing in front elevation the platen of a type-writing machine and the position the vertical roll holder occupies with respect thereto. 40 Fig. 2 is a sectional elevation of the roll holder.

Located in any convenient position adjacent to and preferably, although not necessarily, below the machine is a support 10 carrying an upright rod 11 in a plane substantially perpendicular to the axis of the paper carriage roll 17. A tube 12 is provided to which is fastened a plug 13. This plug 13 is countersunk at its center as shown in Fig. 50 2, and is supported on the upright or vertical rod 11 which forms a pivot for the tube 12. Integral with, or fastened to the tube 12 in any convenient manner, is a dished plate or 55 supporting member 14. The roll of paper is slipped over the tube 12 and rests on the

dished plate 14. The end of the paper is carried under a guard 16 of a movable paper carriage 20. The carriage 20 is provided with wheels 22 which rest on a track 23 along which the carriage is adapted to move. 30 This lateral movement may be provided by means of a suitably driven drum 24 around which a cord 25 may be wound. The cord 25 is secured to rods 26 and 27 carried by carriage 20 and when wound on or off of the 35 drum 24, will impart lateral movement to the carriage and paper. The paper is fed from line to line by means of a toothed wheel 21 carried by the rod 26, the paper being grasped between said teeth and the roll 17. 40 The wheel 21 is provided with a bearing having a square opening therein through which a square shaft 30 extends. The shaft 30 receives motion from any suitable source of power through a gear wheel 31, and it is 45 apparent that such rotary motion is imparted to the toothed wheel 21 and that the paper may thus be moved from line to line 50 as required.

In the operation of the device, the paper is 55 fed from the roll and twisted at approximately a right angle toward the front and upwardly, or over itself, as shown at 18, the end of the paper being then carried under the guard 16 across the face of the platen 60 and over the roll 17. When the paper is fed by the printer from the roll 15 the force is exerted along the right-hand margin of the strip to the more distant edge or bottom of the roll 15 regardless of the location of the 65 toothed wheel 21. As the carriage 20 moves laterally of the machine, the angle of the paper, at 18, is slightly increased or decreased, but no strain is placed on the paper 70 thereby, and consequently there is no tendency, on the part of the paper, to twist or warp. The paper, therefore, always feeds to the carriage 20 on a line approximately at 75 right angles to the transverse line of travel thereof, without having to be guided in the 80 proper direction by intermediate twisting members, and consequently the tendency of the paper to buckle is greatly lessened and the construction is simplified.

The center of gravity of the roll being below the pivot, the mass of paper is balanced, and as the paper is fed through the printing machine, it unrolls freely and with practically no friction, all tendency of the paper 90 to break, twist or warp, due to the quick 95

movement of the feeding mechanism, and the lateral movement of the paper carriage, being thereby avoided. The roll being balanced and rotating in its center of gravity, 5 there is no tendency on the part of the roll to rewind, as would be the case were the roll swung on a horizontal axis.

The invention claimed is:

1. In a printing machine, the combination 10 with a laterally movable paper carriage of a rotatably mounted rolled strip of paper adjacent thereto, the paper strip being passed from said roll immediately to said carriage by a single partial free twist of the strip 15 over itself and at approximately a right angle, whereby the use of guides for the paper between the roll and carriage is avoided.
2. The combination with a printing machine 20 having a horizontally movable paper carriage, of a paper roll holder rotatably mounted on a vertical axis underneath the machine.
3. In a printing machine, the combination 25 of a laterally movable paper carriage, and a paper roll holder comprising a vertically disposed support, a tubular member encir-

cling said support and pivotally mounted thereon, and a supporting member mounted on the tubular member.

4. In a printing machine, the combination 30 of a laterally movable paper carriage, a paper roll holder comprising a support, rotatable means encircling said support and having at one end a bearing member, and a supporting member mounted on said rotatable member at the end remote from said bearing member.

5. In a printing machine, a laterally movable paper carriage, means for moving the 40 paper across the face of the carriage, in combination with a support vertically disposed with respect to the machine, a paper roll holder pivotally mounted on said support and having a dished supporting plate, 45 whereby the paper may be fed across the paper carriage without tendency to twist or warp.

In witness whereof I hereunto subscribe my name this 9th day of Feb. A. D., 1912.

ARTHUR H. ADAMS.
